UNITED STATES PATENT OFFICE.

RUPERT ELWOOD HARRYMAN, OF LOUISVILLE, KENTUCKY.

SASH-LOCK.

No. 823,775.

Specification of Letters Patent.

Patented June 19, 1906.

Application filed February 18, 1905. Serial No. 246,835.

To all whom it may concern:

Be it known that I, RUPERT ELWOOD HARRYMAN, a citizen of the United States, residing at Louisville, in the county of Jefferson and State of Kentucky, have invented a new and useful Sash-Lock, of which the following is a specification.

My invention relates to devices for locking window-sash; and the objects of my improvement are to provide a portable sash-lock, simplicity of construction and operation, inexpensiveness, effectiveness, and to provide a sash-lock that will lock either or both sash either in a closed or partly-open position. These objects I attain by means of the device illustrated in the accompanying drawings, in which—

Figure 1 is an elevation showing the lock in position; Fig. 2, a detail view of a modification; Fig. 3, an edge view, and Fig. 4 a horizontal section on line A B of Fig. 1.

Similar reference-numerals refer to similar parts throughout the several views of the drawings.

The integral legs and handles 1 and the base-plate 2 constitute the body of the device. The legs 1 are pivoted on base-plate 2 by means of rivets 4, and the feet 3 are pivoted to the end of legs 1 by means of rivets 5. A wire spring 7 is coiled about and held in position by a rivet or post 6, secured in base-plate 2.

8 represents the portion of the window-frame in which the sash slide.

9 is the top cross-rail of the lower sash, and 10 the bottom cross-rail of the upper sash.

11 is the window-stop.

The free ends of legs 1 beyond rivets 4 extend outward and serve as handles 15 for manipulating the device. These handles are somewhat turned in toward each other, so that the inner portion is curved and forms a groove adapted to receive the free ends of spring 7. Concentric with rivets 4 are arranged gear-teeth integral with legs 1 and intermeshing, which serve to preserve the symmetrical relation of the legs with relation to base-plate 2. It will be seen that the free ends of spring 7 pressing against the handle portions of legs 1 have a tendency to force said handles apart, and this results in bringing the feet 3 at the free ends of legs 1 toward each other. The feet 3 being pivoted on rivets 5 always accommodate themselves

55 to the vertical flat surface of the upper sash, against which they press, whatever may be

the angular relation of the legs. The base 2 is adapted to press against the inner edge of stop 11, against which the lower sash slides, and its extensions are bent at an angle at 60 each end, adapting them to rest upon or otherwise engage the top of the top cross-rail 9 of the lower sash. Both extensions of base-plate 2 are bent at an angle in order that the device may be used on either side of the window as may be most convenient and need not be made rights and lefts. 12 is the parting-strip, 13 the side rail of the upper sash, and 14 the sash-cord.

The manner of using my improved sash-lock will now be understood. The handles are grasped with the thumb and first finger and pressed together against the action of spring 7, thus spreading feet 3 apart and thereby decreasing the distance between 75 feet 3 and the bearing-surface of base-plate 2. In this condition the lock may be placed against the surface of window-stop 11 and parting-strip 12 with the feet pressing against the inner surface of the side rail 13 of the upper sash and the serrated bearing-surface of base-plate 2 engaging the surface of the window-stop, against which the lower sash slides. The angular end of the extension of plate 2 is placed upon the top rail 9 of the lower sash if 85 said sash is to be kept closed and the handles are released. The upper sash is thus secured in whatever position it may be against movement in either direction, and the lower sash is held down at the same time. If it is intended to have both sash partly open before placing the lock in position, the upper sash is drawn down to the required position and the lock placed against it at a suitable distance 90 above the lower sash. The upper sash will 95 now be locked in that position, and the lower sash may be raised till the top rail engages the angular extension of plate 2. It will be understood that the device may be placed either by the right hand or the left 100 hand on either side of the window by simply reversing it and placing the corresponding angular extension of plate 2 upon the top rail 9 of the lower sash.

This sash-lock is portable, not being fastened to the sash or to the window-frame, and is therefore adapted for use by tenants and others who are not permanently located and have occasion to change their domicile more or less frequently.

Having thus described my invention so that any one skilled in the art pertaining

thereto may make and use it, I do not desire to claim spreading legs and pivoted feet broadly in a device of this class, because I am aware that these have been used; but

5 I claim—

1. A portable window-sash lock comprising in combination a base-plate, a pair of diverging legs and integral handles pivoted on said base-plate, a spring pressing against and 10 adapted to spread said handles and converge said legs, a pivoted foot on the end of each leg adapted to engage the sash, said base-plate provided with an extended portion disposed in a plane at right angles to the plane 15 of said legs having its outer surface serrated or roughened and adapted to engage the window-stop and having its extended ends bent at an angle and thus adapted to engage the

top rail of the lower sash, substantially as specified.

2. As an article of manufacture, a portable sash-lock, comprising a base-plate, means for engaging the inner face of the side rail of the upper sash and securing it against movement in either direction consisting of spreading legs pivoted on said base-plate and feet 20 pivoted on said legs, corresponding means for engaging the window-stop provided by said base-plate, and means for engaging the top of the lower sash and securing it against 25 upward movement provided by extensions of said base-plate, substantially as specified.

RUPERT ELWOOD HARRYMAN.
